United States Patent Office.

S. O. CAMPBELL, OF TIPTON, MISSOURI.

Letters Patent No. 97,876, dated December 14, 1869.

IMPROVED RAILWAY-CAR COUPLING.

The Schedule referred to in these Letters Patent and making part of the same

To all whom it may concern:

Be it known that I, S. O. CAMPBELL, of Tipton, in the county of Moniteau, and State of Missouri, have invented a new and improved Car-Coupling; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved car-coupling.

Figure 2 is a plan or top view, partly in section, of the same.

Similar letters of reference indicate corresponding parts.

This invention relates to a new car-coupling, which is so arranged that it will be self-coupling, and that it will retain the coupling-pin ready to lock as long as the link is not inserted.

The invention consists, chiefly, in the use of a pivoted perforated plate, which is arranged within the coupling-box, and which hangs vertical when the car is uncoupled, sustaining the coupling-pin on its upper end.

When the link is inserted, it strikes either the upper or lower arm of said plate, and swings the same into the horizontal position, thereby bringing its aperture under the pin, which will drop to lock the link.

A great advantage of this invention is, that it couples entirely automatic, and another, that it is adapted to lock high and low cars together, as the link can enter the coupling-box either above or below the partition to which the plate is pivoted.

A, in the drawing, represents the coupling-box, made of a continuous strap, *a*, bent U-shaped around the supporting beams *B C*, and of the front mouth-piece *b*, as shown.

Into this box is fitted a horizontal partition, *D*, which may also be made of one plate, doubled up

where it forms the partition, and bent up and down at the ends, to form an abutment for the link.

This partition *D* has a four-sided aperture in it, and supports a plate, *E*, which is, by a transverse pin, *e*, pivoted in the slot, as shown.

This plate *E* is heavier at one end, and will therefore hang perpendicular, as in fig. 1.

Directly above it is, in the box *A*, an aperture for the coupling-pin *F*, which pin is supported in the upper end of the plate *E*, as shown.

When the coupling-link *G* is inserted in the box *A*, either above or below the partition *D*, it strikes against the upper or lower part of the plate *E*, and swings the same into a horizontal position, thereby bringing an aperture, which is in the middle of the plate *E*, in line with the coupling-pin, causing the latter to drop and lock the link.

When the pin is raised to uncouple, the plate *E* will resume its vertical position, and will again sustain the pin for the next coupling.

The beams *B C* are held apart by a spring, *H*, wound around a guide-pin, *I*, and serve, therefore, as cushions for the couplings.

Having thus described my invention,

I claim as new, and desire to secure by Letters Patent—

1. The perforated plate *E*, pivoted in a partition of a coupling-box, and weighted at one end to hang vertical, and to sustain the coupling-pin as long as the link is not introduced, allowing the link to be applied either above or below the said partition, as specified.

2. The perforated partition *D*, arranged in a coupling-box, for supporting the weighted pivoted perforated plate *E*, as set forth.

S. O. CAMPBELL.
